STRAPPING TOOL

**Helmut W. Waldorf, New York, N. Y., assignor
to The Wire and Steel Products Co., Inc.,
Brooklyn, N. Y.**

Application July 9, 1935, Serial No. 30,579

8 Claims. (Cl. 81—9.1)

This invention relates to a strapping tool and has for its object to provide, in a manner as hereinafter set forth, a tool of the class referred to for expeditiously strapping and sealing 5 a binder element around a package.

A further object of the invention is to provide, in a manner as hereinafter set forth, a tool for the purpose referred to including an actuating element for a binder stretcher structure and an actuating element for a binder sealing structure, 10 said elements being carried by a common support, and with said elements disposed in a manner whereby the operator may grasp the binder stretcher structure actuating element for the purpose of holding the tool firmly on the package while the operator is operating the sealing structure actuating element for the purpose of connecting the binder together and for sealing the latter.

Further objects of the invention are to provide, in a manner as hereinafter set forth, a tool for the purpose referred to which is comparatively simple in its construction arrangement, strong, durable, compact, conveniently operated, 25 thoroughly efficient for the purpose intended thereby, readily assembled, quickly repaired when occasion requires, and comparatively inexpensive to set up.

With the foregoing objects in view, and others which may hereinafter appear, the invention consists of the novel combination, arrangement and construction of parts as will be more specifically referred to and as are illustrated in the accompanying drawings wherein is shown an embodiment of the invention, but it is to be understood that changes, variations and modifications may be referred to which fall within the scope 35 of the invention as claimed.

In the drawings:

Figure 1 is a side elevation of the tool in its 40 inoperative position.

Figure 2 is a side elevation of the tool illustrating the sealing structure being disposed in 45 position for actuation to seal the binder or strap,

Figure 3 is an elevation looking towards the outer end of the sealing structure prior to its actuation and with the front plate removed,

Figure 4 is a sectional elevation looking towards the outer end of the sealing structure and 50 with parts thereof illustrated in position for sealing the binder or strap and with the front plate removed,

Figure 5 is a bottom plan view of the form of 55 sealing member forming a part of the sealing structure,

Figure 6 is a fragmentive view in perspective illustrating a band or strap stretched and sealed.

Figure 7 is a fragmentive view in top plan of the tool,

Figure 8 is a section on the line 8—8, Figure 7, 5

Figure 9 is a perspective view of the base of the tool,

Figure 10 is a front elevation, partly in section, 10 of a modified form of sealing structure in active position,

Figure 11 is a side elevation of the structure shown in Figure 10,

Figure 12 is a front elevation of a modified 15 form of sealing structure in inactive position,

Figure 13 is a bottom plan view of a modified 15 form of sealing structure, and

Figure 14 is a fragmentive view in perspective of the binder or strap as it would appear when operated upon by the modified form of sealing structure.

With reference to Figures 1, 2, 3, 4, 7, 8 and 9, more particularly to Figure 9, the tool includes a base 15 formed of a thin plate-like forward section 16, a thin plate-like rear section 17 and a bar-like intermediate section 18 disposed on its lower lengthwise edge and functioning to connect the sections 16, 17 together. The sections 16 and 17 are arranged in parallel spaced relation and have flat-like lower faces for seating upon the package which is to be encompassed by the binder 20 or strap. The section 16 is of greater length than the section 17, has a lengthwise portion thereof, indicated at 19, of less length than its remaining lengthwise portion, indicated at 20.

The section 16 between its transverse median 35 and forward end is formed with a horizontally disposed rectangular opening 21 to provide a clearance for the operation of the sealing elements of the sealing structure, to be referred to, and in this connection attention is directed to 40 Figures 3 and 4. The portion 20 of section 16 has integral with its upper face a pair of parallel spaced ribs 22 forming a binder or strap guide groove 23. The ribs 22 extend from the forward wall of opening 21 to the forward edge of base 15. 45 The ribs 22 are arranged adjacent to opposite sides of the lengthwise median of section 16. The latter has integral with its upper face, in proximity to the rear wall of opening 21, a vertically disposed stop lug 24 for arresting the rearward shift of the head of the sealing structure, to be referred to, and in this connection attention is directed to Figure 2. The lug 24 is formed with a flat forward face 25 and aligns with one of the ribs 22. The face 25 is adapted to abut the head 50

of the sealing structure, and in this connection attention is directed to Figure 2. The rear of portion 20 of the section 16 has arranged there-over a support in the form of a block 26 which is spaced adjacent to the edges of such portion 20. The block 26 is formed with an upstanding forwardly inclined front part 27 having near its upper corner a transverse opening 28 intersected by a furcation 29 opening at the top and forward 10 end of the block. The part 27 provides for disposing the head of the sealing structure, when the latter is inactive, at a downward inclination and in this connection attention is directed to Figure 1. The part 27 further provides for supporting the pivot, to be referred to, for connecting the head of the sealing structure to the block 26, and in this connection attention is directed to Figures 1 and 2. The part 27 has each side formed with a laterally disposed annular boss 30 20 registering with the wall of opening 28. The bosses 30 form continuations of the wall of opening 28 and act as spacers between the head of the sealing structure and the part 27 of block 26 when the said head is pivotally connected to block 26, and in this connection attention is directed to Figure 1. The block 26 also includes an upstanding rear part 31 integral with the rear side of and less height than the part 27. The part 31 constitutes a stop for a purpose to be referred to. The block 26 further includes a laterally extending part 32 which is integral with the inner sides of the parts 27 and 31. The part 32 is of less height than and provides a lateral extension which is common to the parts 27 and 31. 35 The block 26 is formed with a threaded transversely disposed socket 33 arranged in the parts 27 and 32 and extending into the part 31. The socket 33 opens at the inner side of block 26. The socket 33 is for receiving a holdfast device, to be referred to, for anchoring one end of a side cheek, to be referred to, to the block 26 and in this connection attention is directed to Figure 7. The rear end of section 16 is of reduced thickness with respect to the remaining portion thereof. One side and the rear end of section 16 is 40 beveled as at 34.

The section 17 has formed integral with its upper face, a vertically disposed part 35 constituting a support and which is to have secured there-to several elements, to be referred to, of the tool and in this connection attention is directed to Figures 1 and 2. The part 35 also acts to support the lever, to be referred to, of the stretching structure and in this connection attention is directed to Figures 1 and 2. The part 35 is formed of a stem 36 merging into a head 37 consisting of a forwardly directed downwardly inclined part 38 and a rearwardly directed upwardly inclined part 39 provided at its upper end with a transversely extending threaded opening 40. The part 37 terminates in a forwardly directed downwardly inclined arm 41 having a beveled forward end 42 and a transversely extending threaded socket 43. The opening 40 is adapted to receive an adjustable threaded stop 44 (Figures 1 and 2) which projects outwardly from the outer side of part 39 and is employed for a purpose to be referred to.

The section 18 is disposed lengthwise with respect to the base 15 and it consists of a bar 45 having an enlarged forward end portion 46 which is integral with the portion 20 of section 16 and also integral with the outer side of block 26. The bar 45 couples the sections 16 and 17 together and maintains said sections in spaced relation.

The end portion 46 of section 18 has a transverse opening 47 for receiving the shaft, to be referred to, of the stretching structure and in this connection attention is directed to Figure 7. The bar 45 includes a downwardly curved rear end portion 48 and an intermediate portion 49 which connects the portions 46 and 48 together. The rear end portion 48 of bar 45 is integral with the outer side of extension 35 and the upper face of section 17. The inner side of intermediate 10 portion 49 of section 18, in proximity to its lower end, has integral therewith a lateral disposed socket forming member 50 for receiving a spring controlled pawl support, to be referred to, and in this connection attention is directed 15 to Figure 8.

The section 16 rearwardly of the part 32 of the block 26 has an opening 51 and anchored into the latter is a disc 52 extended above portion 20 of section 16 and formed with a serrated or toothed upper face 53 for a purpose to be referred to. The section 17 of the base 15 is formed in its lower face with a guide groove 54 for the binder or strap.

Positioned against the part 32 of block 26 and 25 the arm 41 of extension 35 is a side cheek 55 through which extends holdfast means 56, 57. The holdfast means 56 engages with the wall of the socket 33 and the holdfast means 57 engages with the wall of the socket 43 whereby one end 30 of cheek 55 is secured to one side of block 26 and its other end to the corresponding side of the vertically disposed or upstanding part 35. The cheek 55 also constitutes a support for a purpose to be referred to. The cheek 55 has an opening 35 58 which aligns with the opening 47 in the section 18 of the base 15. The arm 41 of extension 35 is of greater width than the part 38 of the head 37 whereby the arm 41 will align with the part 32. The cheek 55 has openings 40 40 for the passage of the holdfast means 56, 57. These openings are not shown.

The tool includes a binder or strap stretching structure 59 which includes a rotatable holding element 60 of disc-like form having its edge provided with a pair of circumferentially extending spaced rows, 61, 62 of grippers and between said rows the edge of element 60 is formed with a circumferentially extending row of ratchet teeth 63. The teeth 63 are set inwardly with respect 50 to the grippers. These latter are teeth of tapered contour and of the same form as the teeth on disc 52. The grippers 61, 62 coact with the teeth 53 for the purpose of stretching the binder or strap when the element 60 is revolved in a clockwise direction. The element 61 is loosely mounted upon an eccentric portion 64 of a shaft 65 journaled in the openings 47, 58. One end of shaft 65 has a head 66 which abuts against the outer side of the section 18 of base 15. The other end of shaft 65 extends laterally from the cheek 55 and carries a retaining nut 67 and a washer 68. Fixed to shaft 65 for the purpose of rotating it is the hub 69 of a handle member 70. The hub 69 is interposed between the washer 68 and the side cheek 55. The purpose of the handle member 70 is to rotate shaft 65 for elevating and lowering the element 60 relative to teeth 53, for the purpose, when element 60 is lowered, to coact with the teeth 53 for gripping 70 the binder or strap to stretch the latter when the element 60 is intermittently revolved, by a means to be referred to, in a clockwise direction.

Loosely mounted on the shaft 65 between the section 18 of base 15 and the side cheek 55 is 75

the bi-furcated forward end 71 of a lever 72 which extends rearwardly from shaft 65 and normally seats on the head 31. The bi-furcated forward end 71 of handle 72 is formed with a pair of upstanding parallel apertured ears 73 carrying a fixed stub shaft 74 arranged rearwardly with respect to element 60. Loosely mounted on shaft 74 is a spring controlled dog 75. The latter extends upwardly and downwardly with respect to shaft 74 and is formed at its lower end with a nose 76 for the purpose of intermittently engaging with the teeth 63, to intermittently revolve element 60 on the cam portion 64 of shaft section 65. The controlling spring for the dog 75 is indicated at 77. Fixedly secured to the socket forming member 50 is a headed stub shaft 78 upon which is mounted a spring controlled lock pawl 79 extending towards the teeth 63 for the purpose of intermittently engaging therewith to arrest anti-clockwise movement of the element 60. The pawl 79 is formed with a nose 80 to engage teeth 63. The controlling spring of pawl 79 is indicated at 81. The lever 72 is of the oscillatory type and functions, in connection with the dog 75 and the teeth 63, to intermittently revolve element 60 when the latter is lowered relative to the teeth 53 of disc 52.

30 The hub 69 of the handle member 70 (Figures 1 and 2) has a shoulder 82 which coacts with a stop 83 carried by the side cheek 55 for the purpose of arresting the shifting of handle member 70, in a forward direction. The lug 83 also coacts with the side edge of a handle member 23 70 for arresting the shifting movement of the latter in a rearward direction. The handle member 70 has a hand grip 84.

The tool also includes a sealing structure for connecting and sealing the overlapping ends of the binder or strap together after the latter has been stretched by the structure 59. With reference to Figures 1, 2, 3, and 4, the sealing structure, generally indicated at 85, consists of a head including a casting 86 formed of a pair of side members 87, 88 and a back member 89 of less height than the side members. The upper end portions 90 of the side members are tapered and formed with aligning openings 91. Each of the side members is cut away to form a shoulder 92, an abutment edge 93, a shoulder 94 and an abutment edge 95. The shoulders 92 are arranged in parallel spaced horizontal planes. The abutment edges 93 and 95 are arranged in parallel vertical planes. The shoulder 94 is of greater length than the shoulder 92. The edge 93 extends from the inner end of the shoulder 92 and terminates in the outer end of shoulder 94. The edge 95 extends from the inner end of shoulder 94 and terminates at the bottom edge of a side of the casting. The sides 87, 88 are formed with rearwardly extending parallel apertured spaced ears 96, only one of which is shown. The abutment edges 93 are formed with threaded sockets 97 between the shoulders 92, 94. Positioned against the shoulders 92, the abutment edges 93, and the shoulders 94 is a front plate 98 which has its lower end flush with the lower edge of the side members 87, 88. The plate 98 is formed for a portion of its length with a pair of spaced inwardly directed flanges 99, only one shown, and which abuts the outer end portion of the shoulders 94 and are spaced from the abutment edges 95. Extending through the apertured ears 96, as well as being fixed thereto, and 75 also extending through the opening 28 is a pivot

100 for the casting 86. The front plate 98 is anchored to the side member 87, 88 by holdfast devices 101, only one shown, and which engage in the sockets 97. The lengthwise edges of the flanges 99 of the front plate 98 coat with the abutment edges 95 of the side members and with the shoulders 94 to provide a pair of elongated slots 102 opening at the bottoms of the side members. The casting 86 coats with the front plate 98 to form a chamber 103 to receive elements, to be referred to, of the sealing structure, the chamber 103 being open at its top and at its bottom.

Fixed in the openings 91 is a pivot shaft 104 for a purpose to be referred to. The pivot shaft 104 extends across the top of the chamber 103. Arranged within the latter is a slide 105 having its upper portion formed centrally with a furcation 106 lengthwise thereof and its lower portion provided with a horizontally disposed furcation 107 opening at its sides and its bottom. The slide 105 is of U-shaped contour and in proximity to each lower corner thereof has fixed thereto a pivot extending across the furcation 107. The pivots are indicated at 108, 109. Extending into the furcation 107 is a pair of oppositely disposed links 110, 111 mounted at their upper ends upon the pivots 108, 109. The outer side edges of the links intermediate their ends are incurved, as at 112, to provide clearances 30 when the links are extended relatively to each other on the downward movement of slide 105 by an actuating means therefor, to be hereinafter referred to. When the links are extended, they move in opposite directions relatively to each other through the slots 102. Arranged within the slots 102 are oppositely movable sealing elements 113, 114 which function not only to anchor or connect the overlapping end portions of the binder or strap together, but also seal the 40 binder or strap. The elements 113, 114 are of like construction and but one will be described, as the description of one will apply to the other. Each sealing element is of greater length than the slot 102 in which it is arranged and it extends below the bottom of casting 86. Each sealing element consists of a substantially oblong body part 115 having a squared outer edge 116 and a rounded bottom edge 117. The upper end of body part 115 is bi-furcated, as indicated at 118, and carries a fixed pivot 119 which extends across the furcation. The lower end of the link 110 or 111 is connected to a pivot 119. The body part 115 at the lower portion of its inner side is formed with a furcation 120 and with the 50 walls of the latter incut, as at 121 to provide edge portions for lifting the strap against the bottom of an abutment element to be referred to. The body part 115 adjacent its lower end has a transverse opening 122 which communicates at 60 its inner end with the furcation 120. The upper portion of the inner edge of body part 115 is rounded, as at 123. An intermediate portion of the inner edge of body part 115, as indicated at 124, is squared. That portion of the inner edge of body part 115 between edge portions 123 and 124 is inset, as at 125, to form a clearance. The body part 115 between its transverse median and lower end is mounted on a pivot 126 which is fixed 65 to the back 89 of casting 86. The pivot 126 extends into a cutter member 127 for anchoring the latter within the opening 122 in which member 127 is arranged. The member 127 extends 70 through and beyond the furcation 120 and op- 75

poses the incut portions 121 of the walls of the furcation 120.

Anchored to the back 89 of casting 86 is a centering rod 128 which is disposed at the lengthwise center of said back 89 in proximity to the lower end of the latter. Mounted on the rod 128 is an abutment element 129 formed with an opening 130 for the passage of a hold-fast device 131. The latter extends through the back 89 and has threaded engagement with the front plate 98, as at 132. The abutment member has oppositely disposed incurved side parts 133 and oppositely disposed cutouts 134 to receive the inner ends of cutter members 127 during the cutting operation. The cutouts 121 form clearances for the elements 112, 113 for receiving the binder or strap during the sealing operation. In this connection see Figure 4. The cutouts provide for the elements 113, 114 acting to overlap the seal 135 with respect to the overlapped end portions 136, 137 of the binder or strap 138. The cutters 127 function to slit the seal 135 at opposite sides and to compress the portions 139 freed by the slitting inwardly at the same time to clamp the binder or strap 138 whereby the overlapped end portions 136, 137 of the binder or strap 138 are securely connected together, as well as being sealed. The members 127 have curved inner ends 140 which correspond to the curvature of the inset portions 134 of the member 129.

The slide 105 is vertically moved from the position shown in Figure 3 to the position shown in Figure 4 to provide for the simultaneous operation of the elements 113 and 114. The means for vertically shifting the slide 105 consist of a link 141 which extends into the furcation 106 and has its lower end mounted on a pivot 142 carried by slide 105. Mounted upon pivot shaft 40 104 is a shiftable head 143 formed with a furcation 144. The upper end of link 141 is mounted upon a pivot 145 carried by head 143. The pivot 145 is normally out of alignment with the pivot 142, that is to say, the pivot 145 is disposed outwardly with respect to the pivot 142 and in this connection see Figures 1 and 2. The head 143 extends beyond the upper end of the casting 86 and is formed at one side with a lateral extension 146 which overlaps the top edge of side 87 of the casting 86. Integral with the extension 144 is a lever arm 147 which normally extends rearwardly from casting 86. The lever arm 147 has its rear end provided with a hand grip 148. The lever arm normally abuts the stop 44 and in this connection see Figure 1. When lever arm 147 is in its normal position, the casting 86, together with the parts carried thereby, is swung on the pivot 100 and disposed at an inclination with respect to lever arm 147 and also seats on the portion 27 of the block 26.

The dog 15 is adapted to contact with the part 31 of the block 26 to arrest the forward movement of lever 72. The sealing structure, when moved to active position has the housing thereof disposed vertically, extended into the opening 21 to bear upon the strap or binder and abut the lug 24. The housing of the sealing structure is not moved to the position referred to until the stretching structure has acted upon the strap or binder. When the housing of the sealing structure has been moved to the position aforesaid, the actuating element or lever 147 is swung forwardly from its position shown in Figure 2 whereby the sealing structure will be actuated 75 to apply the seal to and connect the end terminal

portions of the binder or strap together. The housing of the sealing structure is swung from its inclined position to and from its vertical position as aforesaid by the actuating element or lever 147.

With reference to Figures 10, 11, 12, and 13, the modified form of sealing structure illustrated thereby includes an open top and bottom housing 149 having its sides 150, 151 of greater height than its front 152 and its back 153. The sides 150, 151 are formed with lengthwise extending slots 154, 155 respectively, which open at the bottom of the housing 149. Positioned within and extending from the lower ends of slots 154, 155 is a pair of oppositely disposed shiftable 15 sealing elements 156, 157 respectively, which contact with two oppositely disposed pairs of spaced cutter members 158, 159 respectively, depending and extending laterally from an abutment member 160 anchored within the lower portion of the 20 housing 149. The members 158, 159 depend below the lower end of housing 149 and extend towards the elements 156, 157 respectively. The abutment member 160 has a tapered lower portion 161 formed with oppositely curved sides 162. 25 The lower end of the body of member 160 is flush with the lower end edges of the housing 149.

The elements 156, 157 are of like form and each consists of a body part 163 formed with a 30 bi-furcated upper portion and with the furcation indicated at 163a. The lower end of body part 163 is provided with a set of inwardly extending parallel spaced tongues 164, 165, 166. The tongue 165 is of greater width than tongues 164, 166. 35 The tongues coact to provide slots 167, 168 for the reception of a pair of cutter members. The tongues of elements 156, 157 coact with the two pairs of cutter members to provide for the seal 169 for the binder or strap 170 to be formed at 40 each side with two spaced pair of slits 171; for overlapping the sides of the end terminal portions 172, 173 of binder or strap 170 by the sides of seal 169; and for compressing the portions 174 of the seal 169 freed by the slits 171 to extend 45 inwardly and to distort parts of the sides of portions 172, 173 whereby the seal 169 is held in clamping relation on the binder or strap 170. When the seal 169 is clamped to the binder or strap 170 the latter is sealed and the binder or strap and end portions 172, 173 connected together to prevent the separation thereof.

The body part 163 of a sealing element has 50 spaced rounded inwardly directed inner edge portions 175, 176 and with the latter arranged adjacent to the tongues. The body parts 163 are mounted upon pivots 177 carried by housing 149 and are adapted to have their lower portions swung inwardly towards each other by a means to be referred to, and when swung inwardly have the tongues coact with the cutter members to 55 form the binder or strap and seal in the manner as shown in Figures 10 and 14. When the binder or strap and seal are to be operated upon by the sealing structure, they are arranged against the cutter members, when the parts of the sealing structure are in the position shown in Figure 12.

Mounted within the housing 149 is a vertically movable U-shaped slide 178 having a transverse furcation 179 in its lower portion. Extending 70 into the furcation 179 is a pair of oppositely outwardly inclined links 180 mounted at their upper ends on pivots 181 fixed to slide 178 and having their lower ends extending into the furcations 75 164 of the body parts 163. The lower ends of

links 180 are mounted on pivots 182 carried by elements 156, 157.

The upper portion of slide 178 is tapered, as indicated at 183, and carried by slide 178 is a pivot 184. Mounted on the latter are the lower ends of a pair of opposed upstanding links 185, 186 which will be more fully referred to.

The upper portion 187 of the sides of housing 149 are tapered. The front and back of housing 149 are of less height than its sides and have their upper ends arranged below the tapered upper portion 187 of the side. The front 152 of housing 149 is in the form of a plate anchored to the housing sides 150, 151 by holdfast means 188 and to the housing back 153 by a holdfast means 189. The latter also anchors the abutment member 160 to housing 149. The member 160 has an opening for the passage of means 189. A positioning pin, rod or bar 190 for member 160 is anchored to the housing back 153, extends through member 160 and into housing front 152. The pin 190 is disposed on the lengthwise median of housing 149. The housing back 153 is integral with the housing sides 150, 151. A pair of non-aligning stops 191 are provided to arrest the upward movement of slide 178. The stops 191 are anchored to and extend inwardly from the inner faces of the sides 150, 151 of the housing 149. The stops are arranged above and outwardly adjacent with respect to pivot 184. The stops 191 are disposed in the path of the upper edges of slide 178.

A pair of oppositely disposed outwardly inclined lever members or handles are indicated at 192, 193, formed at their forward ends with oppositely disposed overlapping inwardly inclined offset extensions 194, 195 mounted intermediate their ends upon a pivot 196 carried by the housing sides 150, 151 in close proximity to the upper ends of the latter. The pivot 196 is disposed at right angles to the pin 190. The extensions 194, 195 are oppositely rabbeted on their inner sides as at 197, 198 respectively, to form said extensions with reduced parts 199, 200 respectively, which oppose the upper portions of the outer sides of the links 184, 185 respectively. The pivots 201, 202 are prevented from being moved to endwise aligning relation by the lever member 192 abutting an adjustable stop 203 carried on the inner sides of lever member 193. The axes of the pivots 201, 202 are offset with respect to the axes of pivots 178, 196. The pivots 178, 196 are arranged in superimposed parallel relation. The stop 203 also prevents the lever members abutting. The normal position of these latter is as shown in Figure 11. The normal position of the modified form of sealing structure is as shown in Figure 12. When the lever members 192, 193 are moved away from each other, from the position shown in Figure 11, the slide 178 is moved downwardly to provide for the shifting of the sealing elements 156, 157 to the position as shown in Figure 10 for the purpose of coacting with the members 158, 159 to apply the seal to and to connect the end terminal portions of the binder or strap together.

The binder or strap is positioned around the package and with the end terminal portions thereof in overlapped relation. The end terminal portions of the strap are extended across the opening 21 and are also arranged between the toothed disc 52 and the holding element 60 of the stretching structure 59. The latter is then operated to provide for the binder or strap to be stretched to snugly engage the package. During

the operation of the structure 59 the sealing structure 85 is in the position shown in Figure 1. After the binder or strap has been stretched to the desired extent the sealing member 169 is then positioned on the overlapped end terminal portions 172, 173 of the strap or binder and with the member 169 located over opening 21. The sealing structure 85 is then swung from the position shown in Figure 1 to the position shown in Figure 2 so as to have the head thereof appear as in Figure 3 with respect to the sealing member and the end terminal portions of the binder or strap. The structure 15 is then operated whereby it will act on and appear as shown in Figure 4 with relation to the seal and binder or strap. The action of the structure 85 will cause the seal and binder or strap to appear as shown in Figure 14.

What I claim is:

1. In a tool for the purpose set forth a sealing structure, a stretching structure, each of said structures being provided with a rearwardly extending pivoted actuating element, a base formed with an opening intermediate its ends and spaced guides for a binder or strap, one of said guides being upon the upper face of the base and the other in the lower face of the base, said base being formed with upstanding means extending from the rear end of the base to a point rearwardly of the forward end of the base, means for pivotally connecting said sealing structure intermediate its ends upon the forward end of the upstanding means, means for revolvably supporting and vertically adjusting said stretching structure mounted in said upstanding means in proximity to the forward end of said upstanding means, said upstanding means being formed with a support and stop, respectively, for the actuating element for the stretching structure and the actuating element for the sealing structure, and said base forwardly of said upstanding means being formed with an opening for receiving the forward end of said sealing structure when the latter is in position to be actuated.

2. In a strapping tool, a lever actuated, revolvable vertically adjustable strap stretching structure, a lever actuated pivotally mounted strap sealing structure, a combined supporting and coupling base common to said structures, said base being formed of a forward section for receiving thereon overlapped end terminal portions of the strap, a rear section and an intermediate section merging into one side of and coupling the said other sections together in tandemwise spaced relation, said front section being formed with an opening for positioning thereover said end terminal portions of the strap and to form a clearance for the operation of the sealing structure upon said terminal portions when the sealing structure is shifted to a position for actuation, an upstanding block integral with one side of said front section rearwardly of said opening in said front section for supporting said sealing structure when the latter is in inactive position, said block being formed at its forward end with an opening, means extending through the opening in the block for pivotally connecting the sealing structure adjacent the forward end of the forward end of the latter to said block, said intermediate section being formed with an opening, means extending through the opening in said intermediate section for revolvably supporting said stretching structure over said end terminal

portions, an extension means on said rear section providing a support for the actuating lever of the stretching structure when the latter is inactive, means carried by said extension to provide a stop for the actuating lever of the sealing structure when the latter is inactive, said rear section having its lower face provided with means for overlapping a portion of the strap which is to be stretched and sealed, and a side cheek secured to said block and the extension on the rear section and provided with an opening for the passage of the means which revolvably supports the stretching structure.

3. In a strapping tool, a base formed with an opening, a vertical block on the base and having its lower end disposed rearwardly of said opening, said block including a bifurcated forwardly extending upwardly inclined portion having its top constituting a support, a bodily shiftable sealing structure including a head open at its forward and rear ends and carrying a strap sealing mechanism, said head being provided intermediate its ends with extended spaced ears arranged at the sides of said portion and having its sides extended rearwardly from its front and back, means for pivotally supporting said ears at the sides of said portion, said head being supported on the top of said portion when said structure is in inactive position and for extension in said opening when the sealing structure is active to seal the strap, said structure including an actuating lever for operating the sealing mechanism and for shifting said head on its pivot into said opening, said lever being formed with a forward terminal portion extending between the rear ends of the sides of the head and pivotally connected to said head and to said mechanism, and means on the base rearwardly of the block to provide a stop for the said lever when said structure is in inactive position.

4. In a strapping tool, a base including flat front and rear sections and an upstanding intermediate section integral with corresponding sides of said other sections for coupling the latter together in spaced relation to provide an opening intermediate the ends and opening at one side of the base, said front section being formed with an upstanding block forwardly of said intermediate section, said intermediate section having on its inner side an upstanding front and an upstanding rear lateral offset part aligning with each other and with the upstanding part of greater thickness than the said other offset part, said front offset part being rearwardly of and inset with respect to the inner side of said block, a side cheek secured against the said side of the block, extending across said opening and secured against said rear part, said cheek being spaced from said front offset part, a strap stretching structure including an intermittently revolvable vertically adjustable strap stretcher element arranged between the cheek and the front offset part, a stationary strap gripper means and an oscillatory means for intermittently revolving said element, an adjustable shaft having a central part and end parts disposed eccentrically to said central part, said end parts journaled in said front offset part and cheek and said central part revolvably supporting said element and loosely supporting one end of said oscillatory means between said front offset part and said cheek, said gripper means being arranged in said front section below said element, a stop means for said element carried by said intermediate

section and extended into said opening, one of the end parts of said shaft being extended laterally of said cheek, means carried by said extended end part for adjusting the shaft to vertically adjust said element relative to said gripper means, and said rear offset part having its top constituting a support for said oscillatory means when said structure is in inactive position.

5. In a strapping tool, a strap stretching mechanism including a revolvable holding element, shifting means for the latter, a bodily shiftable strap sealing structure including a head and an actuating lever therefor, a base formed of a front and rear section spaced from each other, an upstanding block integral with said front section, and upstanding part rearwardly of the block and integral with said sections for coupling them together, a vertically disposed part integral with said rear section and with the rear end of the inner side of said upstanding part, a side cheek connected at one end to one side of the block and at its other end to the corresponding side of the said vertically disposed part, said cheek being spaced from said upstanding part, means carried by the forward portion of said upstanding part and said cheek for revolvably supporting and connecting said holding element and shifting means respectively between and with said upstanding part and cheek, said vertically disposed part constituting a support for said shifting means when the stretching mechanism is moved to non-stretching position, said block being formed with a forwardly extending upwardly inclined part having an opening in proximity to its forward upper corner and providing a seating for said head when the sealing structure is moved from sealing position, means extending through said opening for pivotally connecting said head, intermediate its ends to said block, said front section being formed with an opening for receiving the forward end of said head when the sealing structure is in sealing position, and means carried by said vertically disposed part to provide a stop for the downward movement of the lever of the sealing mechanism when the latter is moved from sealing position.

6. In a strapping tool, a base having an upstanding integral block thereon intermediate its ends, a housing open at its top and bottom and being provided with side walls, the side walls intermediate their length and adjacent their rear being provided with ears opposing opposite sides of the block, said housing having the forward portion of its sides provided with slots opening at the forward end thereof, said housing, when the tool is in inactive position being seated on the top of said block, means for pivotally connecting said ears to said block, an anvil within the housing and disposed centrally relative to the said forward portion, spaced from said housing sides for mounting on the strap to be sealed, a pair of spaced oppositely disposed shiftable sealing members of like form positioned in said slots, extending from the open ends of said slots, pivotally supported from the sides of the housing and arranged in parallel spaced relation to opposite sides of said anvil, each of said members having its inner sides formed with a furcation disposed diagonally with respect thereto, downwardly inclined, inwardly extending cutters fixed to said members and extending between and beyond the furcations, the inner edges of said members being formed with V- 75

- shaped cutouts opening into said furcations through the side walls of these latter to provide edge surfaces above the lower ends of said members for holding the strap against the bottom of the anvil, said cutters having inclined cutting edges at their inner ends, said anvil having opposite sides thereof provided with means for receiving the inner ends of the cutters when said members having their forward ends shifted inwardly towards the anvil to act on the strap, a slide movable lengthwise of the housing, oppositely disposed links pivotally connected to the forward end of the slide and to the inner ends of said members, and a shifting structure for the slide pivotally supported from and within the housing and pivotally connected with the slide.
7. In a strapping tool, a sealing structure including an open top and bottom housing having a front, a back and a pair of sides extending above said front and back, the sides of said housing being provided lengthwise with parallel slots opening at the bottoms thereof, a vertical anvil anchored within the lower portion of the housing and being provided on its bottom face with two oppositely disposed spaced pairs of cutter members substantially of triangular contour depending from and extending laterally with respect to opposite sides thereof, said anvil having a tapered lower portion, a pair of oppositely disposed sealing elements positioned in
- 5

said slots, opposing in spaced relation said anvil and extended from the open ends of said slots, each of said sealing elements having its lower end formed with an inner inwardly extending and a pair of outer inwardly extending strap lifting tongues all arranged in parallel spaced relation and below said anvil, each of said sealing elements being bifurcated at its upper end and pivotally connected adjacent its tongues to one of the housing sides, said sealing elements 10 having their tongues coacting with said members, when said elements are swung inwardly to provide the overlapping end portions of a strap and a coupler for said end portions of the strap with a series of slits at each side of the 15 strap and coupler, a slide mounted in said housing, shifting links for said sealing elements pivotably connected to the slide and to the bifurcated ends of said sealing elements, pressure exerting means for the slide pivotably connected 20 to the sides of the housing, and means for pivotably connecting the pressure exerting means to said slide.

8. The invention as set forth in claim 7 having the inner tongue at the outer end of each sealing 25 element of greater width than the outer tongues, and with the space between each outer tongue and the inner tongue being of the same width.

HELMUTH W. WALDORF. 30
